DUSTING APPARATUS

Robert J. Streif, Modesto, and Milton S. Robertson, Campbell, Calif., assignors to Independent Crop Dusting, Inc., San Francisco, Calif., a corporation of California

Application August 31, 1937, Serial No. 161,778

9 Claims. (Cl. 43—147)

Our invention relates to apparatus for dusting crops from an airplane; and the broad object of the invention is to provide a dust disseminating unit by which the dust is given the desired 5 lateral and downward flow.

Another object of our invention is to provide adjustable means for changing the flow characteristics of the unit.

The invention possesses other objects and features of advantage, some of which, with the foregoing, will be set forth in the following description of our invention. It is to be understood that we do not limit ourselves to this disclosure of species of our invention, as we may adopt various 15 embodiments thereof within the scope of the claims.

Referring to the drawing:

Figure 1 is a side elevational view, partly in section, showing the dusting apparatus embodying our invention; and

Figure 2 is a rear elevational view of the same.

In terms of broad inclusion, the dusting apparatus embodying our invention comprises a tube adapted to be mounted longitudinally of an airplane, so that a stream of air may flow through the tube; and means are provided for admitting dust into the air stream. The tube is shaped to conform with the lower half section of a Venturi tube, thus eliminating the reduced 25 pressure area along the top of the discharge opening, and causing all of the dust to be directed laterally and downwardly. A plate is also adjustably mounted adjacent a trailing edge of the 30 tube, to further control the flow of dust from the 35 tube.

In greater detail, and referring to the drawing, the dusting apparatus embodying our invention comprises a tube 2 adapted to be mounted longitudinally on an exterior surface of an 40 airplane, such as on the under side of the fuselage as indicated by the dot and dash line 3 in Figure 1. The tube so mounted provides a channel for a stream of air, and the dust to be distributed by the apparatus is admitted into the air stream in 45 the tube through a duct 4. Any kind of finely divided material may be dusted on a crop by means of such apparatus, and when the plane flies over a field the discharging dust travels down upon the crop.

The important thing with this type of equipment is to get the dust to travel out in a fan shaped flow which is directed downwardly, not upwardly. Tubes used for this purpose have been ordinary Venturi tubes, and the trouble with 55 these is that the dust is directed upwardly as

well as downwardly. The upwardly dispersed dust travels around the body of the plane and even upwardly over the stabilizer in some cases.

In order to avoid this, our tube has the shape of the lower half section only of a Venturi tube. 5 The tube is preferably of rectangular shape, and has a flat top wall 6; the side walls 7 and bottom wall 8 being concave to conform to the lower half section of a Venturi tube. Duct 4 opens into the tube through the top wall 6, and is positioned so 10 that the inlet is adjacent the throat of the tube. By this shape of tube the reduced pressure area along the upper part of the discharge opening, which is characteristic of the ordinary Venturi tube, is eliminated and the dust is all directed 15 laterally and downwardly.

In order to further control the discharging dust from the tube, we preferably provide a plate 9 hingeably connected adjacent the lower trailing edge of the tube on a cross rod 11. This flow 20 control plate extends outwardly as a continuation of the bottom wall 8, and may be adjusted to any desired position with respect to the discharge opening. For purposes of this adjustment a curved rod 12 is fastened to each end of the 25 plate, on a reinforcing bar 13, and the rods are held by suitable clamps 14 fastened to reinforcing bars 16 on the side walls of the tube. By this arrangement the plate is held in a selected 30 position of adjustment; and notches 17 provided in the rods and engageable by the clamps insure that the plate is positively held.

The action of this plate is to create a reduced pressure area behind it, thus further reducing the pressure at the lower trailing edge of the 35 tube. This tends to further pull the discharging dust downwardly, and the extent of this downward directing action depends upon the position of the plate. Thus in the position shown in Figure 1 the dust is directed down a certain 40 amount, and if the plate is rotated further clockwise the dust will be pulled down a still greater amount. As the plate is adjusted further clockwise the pressure behind it becomes reduced to a point where there is a violent turbulent or burbling action imparted to the discharging dust. These varying degrees of reduced pressure at the trailing edge of the tube thus permit an operator to adjust the apparatus to best advantage for disseminating the dust, to compensate for 45 the different slip stream characteristics of different planes and the varying flow characteristics of different dusts.

Furthermore, the adjustable feature of the flow control plate allows it to be set back in line with 55

the bottom wall 8, thereby reducing the drag on the plane when the apparatus is not in operation and the plane is being ferried from one job to another. If desired, a control mechanism may be provided for adjusting the plate 9 by a lever in the pilot's compartment, so that the pilot may change the setting of the plate at any time during flight.

It is further understood that flow control plates similar to plate 9 may also be provided along the trailing edges of side walls 7. These side plates would have the effect of further reducing the pressure at the sides of the discharge opening, thus increasing the lateral dispersemnt of the dust.

In the dust disseminating tube of our invention the forward end of the tube is preferably flared out to provide a scoop for receiving air. For this purpose all the walls may be flared out. In order to keep the top of the tube flat however, we prefer to flare out only the bottom and side walls.

We claim:

1. Dusting apparatus comprising a tube through which a stream of air may flow, said tube in section having the shape of the lower half of a Venturi tube, and an inlet for admitting dust into said air flow.

2. Dusting apparatus comprising a tube through which a stream of air may flow, said tube having a flat top wall, the other walls conforming to the lower half section of a Venturi tube, and an inlet for admitting dust into said air flow.

3. Dusting apparatus comprising a tube through which a stream of air may flow, said tube having

a flat top wall, the other walls being concave, and an inlet for admitting dust into said air flow.

4. Dusting apparatus comprising a tube through which a stream of air may flow, an inlet for admitting dust into said air flow, and a flow control plate adjacent a trailing edge of said tube.

5. Dusting apparatus comprising a tube through which a stream of air may flow, an inlet for admitting dust into said air flow, and a flow control plate extending outwardly from a trailing edge 10 of said tube.

6. Dusting apparatus comprising a tube through which a stream of air may flow, an inlet for admitting dust into said air flow, a flow control plate adjustably mounted adjacent a trailing edge 15 of said tube, and means for holding the plate in a selected position of adjustment.

7. Dusting apparatus comprising a tube through which a stream of air may flow, an inlet for admitting dust into said air flow, and a flow control 20 plate pivotally mounted for adjustment adjacent a trailing edge of said tube.

8. Dusting apparatus comprising a tube through which a stream of air may flow, an inlet for admitting dust into said air flow, said tube having 25 a rectangular discharge opening, and a flow control plate adjacent said opening.

9. Dusting apparatus comprising a tube through which a stream of air may flow, said tube in section having the shape of the lower half of a 30 Venturi tube, an inlet for admitting dust into said air flow, and a flow control plate adjacent a trailing edge of said tube.
